UNITED STATES PATENT OFFICE.

CATHERINE SHEILS, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 17,856, dated November 1, 1887.

Application filed September 21, 1887. Serial No. 250,347. Term of patent 3½ years.

To all whom it may concern:

Be it known that I, CATHERINE SHEILS, of the city, county, and State of New, have invented and produced a new and original Design for a Pattern of a Girl's Costume; and I do hereby declare that the engraved prints accompanying this specification convey to any one accustomed to using paper patterns a clear understanding of how a garment made up by the pattern will appear.

The design shows the fronts meeting at the lower front corners and flaring toward the neck, exposing a pointed vest between them and exhibiting a surplice fullness down the front edges and a pointed lapel extending from the shoulder on either side to the bust, a close-fitting back, a full skirt depending from the

body and exhibiting a broad box-plait at the center of the front, kilt-plaits at either side, and gathers at the back, a deep ornamental lap crossing the lower part of the body at either side and disappearing under a large sash-bow at the back, a standing collar, and coat-sleeves that display full puffs from their tops to below the elbows.

What I claim as my invention, and desire to secure by Letters Patent, is—

The design for a girl's costume, as shown in the engraved prints accompanying this specification.

CATHERINE SHEILS.
